J. B. GURNEY

CHURN DASHER

Filed Jan. 2, 1923

By *Alfred Randolph Jr.* Attorney

UNITED STATES PATENT OFFICE.

JAMES B. GURNEY, OF COLLINSVILLE, ALABAMA.

CHURN DASHER.

Application filed January 2, 1923. Serial No. 610,289.

To all whom it may concern:

Be it known that I, JAMES B. GURNEY, a citizen of the United States, residing at Collinsville, in the county of Dekalb and State of Alabama, have invented certain new and useful Improvements in Churn Dashers; and I do hereby declare the following to be a full, clear, and exact description of the invention, such as will enable others skilled in the art to which it appertains to make and use the same.

The present invention has relation to churns and more particularly to the agitating means whereby the butter cysts are broken up during the process of churning.

In accordance with the present invention, the ordinary and well known form of reciprocating dasher embodying a staff and arms has an auxiliary dasher of peculiar formation applied thereto, the same comprising a spider, and rotary agitators mounted thereon, the same being grouped about the staff and inclined thereto whereby to have an automatic rotary movement imparted thereto as the dasher is reciprocated.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a perspective view of a well known churn dasher having the improvement applied thereto,

Figure 2 is a top plan view of the auxiliary dasher,

Figure 3 is a front view thereof, and

Figure 4 is a detail view of a modified form of hub for the churn dasher.

Corresponding and like parts are referred to in the following description and designated in the several views of the drawings by like reference characters.

The numeral 1 designates the ordinary staff of a reciprocating dasher of well known form and having a head at its lower end comprising arms 2.

The auxiliary dasher comprises a spider embodying a hub 3 and arms 4 radiating from the hub and having their extremities inclined to give the desired set to the rotary agitators. The hub 3 and arms 4 constitute integral parts and, in practice, the hub 3, to which the auxiliary dasher is attached, surrounds the staff 1 and is held thereto by means of a set screw 5 threaded into an opening formed in a side of the hub 3.

Each of the arms 4 is provided with a rotary agitator 6 which is in the form of a propeller wheel, its axle 7 having detachable connection with an arm 4. The arms 4 are uniformly disposed about the hub 3 with the result that the rotary agitators 6 are evenly distributed about the staff 1. The rotary agitators 6 flare upwardly and converge downwardly towards the ordinary head of the dasher comprising the arms 2. The arms 4 have a pivotal arrangement which results in imparting a rotary movement to the agitators as the dasher is reciprocated.

It has been found that a dasher constructed in accordance with the present invention is rapid in operation and quick in action in breaking up the butter cysts, thereby greatly simplifying and reducing the time usually required for churning.

In Figure 4 of the drawings, a modified form of the hub is shown. This hub 3^a is split, and it is secured in position upon the staff 1 by means of a bolt 8 which passes through a pair of ears 9 carried by the hub.

What is claimed is:

1. A dasher comprising a spider including a hub, arms radiating from said hub and having their outer ends inclined upwardly in converging relation, and a rotary agitator applied to the outer end of each of the arms and disposed to converge upwardly and flare downwardly.

2. A reciprocating churn dasher comprising a staff and head and a plurality of rotary agitators grouped about the staff and carried thereby and disposed so as to flare downwardly and converge upwardly, said rotary agitators being positioned above said head and said head comprising laterally extending arms.

3. As a new article of manufacture, an attachment for a dasher, the same comprising a collar to be fitted about and secured to a

dasher staff, arms radiating from said collar, and a rotary agitator carried at the free end of each of said arms.

4. As a new article of manufacture, an attachment for a dasher, the same comprising a collar to be fitted about and secured to a dasher staff, arms radiating from said collar, said arms having their free ends inclined upwardly in converging relation, and

a rotary agitator applied to the outer end of each of the arms and disposed to converge upwardly and flare downwardly.

In testimony whereof I affix my signature in presence of two witnesses.

JAMES B. GURNEY.

Witnesses:

HORACE HAWKINS,
E. I. TARRANT.
